CLAIM

I claim the ornamental design for a light fixture with a LED light unit, as shown and described.

DESCRIPTION

FIG. 1 is a top perspective view of a light fixture with a LED light unit showing my new design;

FIG. 2 is a top elevational view thereof with section lines;

FIG. 3 is a top elevational view thereof;

FIG. 4 is a bottom elevational view thereof;

FIG. 5 is a right side elevational view thereof;

FIG. 6 is a left side view thereof;

FIG. 7 is a front view thereof;

FIG. 8 is a back view thereof;

FIG. 9 is an enlarged cross section view showing a section taken along line 9-9 of FIG. 2;

FIG. 10 is an enlarged cross section view showing a section taken along line 10-10 of FIG. 2; and,

FIG. 11 is an enlarged cross section view showing a section taken along line 11-11 of FIG. 2.

The portions of the light fixture with a LED light unit shown in broken lines form no part of the claimed design.
